UNITED STATES PATENT OFFICE

LOUIS SANTENS, OF SAN FRANCISCO, CALIFORNIA

IRONING DEVICE FOR THE FOLDS OF COLLARS

Application filed May 26, 1930. Serial No. 455,670.

In the laundering of starched or stiff fold-over collars, it is the usual practice to first wash the collar, then to starch it, then to iron it out flat, thereupon to dampen the collar 5 merely along the line where the collar is to be bent over to form the fold in order to soften that part of the collar, whereupon it is folded over and given a preliminary shaping treatment by passing it through a hot tube, after 10 which the softened edge is ironed stiff to final shape. This last step is ordinarily practiced by placing the collar over the end of an almost, but not completely, cylindrical member with the outside fold of the collar without 15 the cylinder, and with the inner fold of the collar within the cylinder, whereupon a complementary heated member is used to iron the fold down against the end of such cylindrical member.

20 The principal object of the invention is to provide a cylindrical member of the kind referred to for use in folding over the collar by ironing it with less strain upon the fabric of the collar, so that there will be a substantially lesser tendency for the collar to crack.

Referring to the drawings forming a part of this specification—

Fig. 1 is a plan view of an ironing device, 30 including my improvement,

Fig. 2 is a vertical sectional view on the line II—II of Fig. 1,

Fig. 3 is an elevation thereof,

Fig. 4 is a top plan view of my novel ironing shaper,

Fig. 5 is a cross section thereof on the line V—V of Fig. 4,

Fig. 6 is a cross section thereof on the line VI—VI of Fig. 4, and

Fig. 7 is an enlargement of details shown on Fig. 2.

The device used for imparting the final shape to the seam or bend of the collar comprises a base 11 suitably supported by legs 12 and, in turn, supporting a cylinder-like member 13. A valve controlled fuel supply pipe 14 leads to a point substantially central of the cylinder to supply fuel for heating the ironing member 15, having a burner 16, the supply pipe 17 which is supplied with fuel

from the pipe 14 through a swivel connection 18, whereby the ironing member 15 may be rotated about the swivel connection 18 and pressed down upon the upper edge of the cylinder-like member 13 by means of a handle 19. 55

Those in control of laundries have desired to impart to the starched, stiff, or semi-stiff turn-over collar a rolled effect at the front, but have been unable to produce such an effect at all; or, in such cases where they have been able to produce such an effect, this has been accomplished in a manner that is altogether too uneconomical for standard practice. I have found that the desired results may be accomplished easily, speedily, and economically by the use of a device of the type described, wherein the member 13 is somewhat wider or thicker at its open ends 20 than at points intermediate thereof and substantially tapering down gradually to about the medial point 21 thereof. Ordinarily, laundries are required to handle collars varying in length from about ten (10) or eleven (11) inches to about seventeen (17) or seventeen and one-half (17½) inches, and I therefore prefer to make the member 13 about two and one-half (2½) inches longer at each end than such maximum length, so that it will not be necessary to exercise too much care in placing the collar thereon. I have discovered that especially good results are obtained when the thickness of the member 13 at the medial point 21 is about one-eighth (1/8) of an inch, this thickness increasing gradually toward both ends of the member for a distance of 60 about eight and one-half (8½) inches up to the points 22, to a thickness of one-fourth (1/4) of an inch, and then extending at each side for a distance of about two and one-half (2½) inches, this last-mentioned part being 65 substantially of the same thickness as at the points 22. It is preferable, but, of course, not essential that the member 13 be shaped to conform to an arc of a circle and, with the dimensions given, I have found that such an arc 70 having a diameter of about nine and three-eights (9¾) inches will produce the desired results.

The member 15 which co-operates with the member 13 to give the parts of the collar 100

adjacent the bend their final shape, has a curved indented portion 23 which co-operates with the top of the member 13, for such purpose. I prefer to so dimension the cut-away portion 23 that it will fit with a slight degree of play over the widest part of the top of the member 13 and to have the ironing member 15 so mounted as to be slightly movable radially. This may be accomplished by making the support for the swivel connection 18 slidable by providing a circular base 24 therefor having a circular flange 25 held in place by a holding member 26 having a flange 27 projecting over the flange 25, there being a slight amount of play possible between the inner edge of the supporting member 26 and the edge of the flange 25. As a result, the inside part of the turned-over edge of the collar may be finished by rotating the handle member 19 in one direction, while pushing or pulling it radially; while the outside part may be finished by correspondingly pulling or pushing while rotating said handle in the other direction. It is, of course, not essential that one direction of rotation be used for the outside of the collar and the other direction for the inside, but this is generally the simplest procedure.

While I have shown and described the preferred embodiment of my invention, it is to be understood that I have done so only by way of illustration thereof and not as a limitation, since changes may be made without departing from the spirit of the invention, the scope of which is defined in the appended claims.

In addition to the advantages already referred to, it is to be noted that turn-over collars are subjected to much less wear and tear, particularly at the front of the fold, when ironed with my invention, due, in part, to the larger surface over which such part of the collar is folded.

Having described my invention, what I claim and desire to secure by Letters Patent of the United States is—

1. An ironing element for use in a collar-fold ironing device comprising a partially cylindrical member open at one side of the cylinder, the thickness of the wall of said member increasing from a point midway the ends thereof toward said ends.

2. An ironing element for use in a collar-fold ironing device comprising a partially cylindrical member open at one side of the cylinder, the thickness of the wall of said member increasing from a point about equidistant from the ends thereof toward said ends, said wall having a rounded edge.

3. An ironing element for use in a collar-fold ironing device comprising a partially cylindrical member open at one side of the cylinder, the thickness of the wall of said member gradually increasing from a point midway the ends thereof toward said ends.

4. An ironing element for use in a collar-fold ironing device comprising a partially cylindrical member open at one side of the cylinder, the thickness of the wall of said member gradually increasing from a point about equidistant from the ends thereof toward said ends. 70

5. An ironing element for use in a collar-fold ironing device comprising a partially cylindrical member open at one side of the cylinder, the thickness of the wall of said member being about one-eighth ($\frac{1}{8}$) inch at about the medial point of said member and increasing gradually to about one-fourth ($\frac{1}{4}$) inch. 75

6. An ironing element for use in a collar-fold ironing device comprising a partially cylindrical member open at one side of the cylinder, the thickness of the wall of said member being about one-eighth ($\frac{1}{8}$) inch at about the medial point of said member and increasing gradually to about one-fourth ($\frac{1}{4}$) inch, the length of said member between the two points where the thickness reaches about one-fourth ($\frac{1}{4}$) inch being about 80 seventeen (17) inches. 85

7. An ironing element for use in a collar-fold ironing device comprising a partially cylindrical member open at one side of the cylinder, the thickness of the wall of said member being about one-eighth ($\frac{1}{8}$) inch at about the medial point of said member and increasing gradually toward both ends to about one-fourth ($\frac{1}{4}$) inch, the length of said member between the two points where said thickness reaches about one-fourth ($\frac{1}{4}$) inch being about seventeen (17) inches, and then extending from each of said two points for about two and one-half ($2\frac{1}{2}$) inches with a thickness of about one-fourth ($\frac{1}{4}$) inch. 95 100

8. In a collar-fold ironing device, an ironing element comprising a partially cylindrical member open at one side of the cylinder, the thickness of the wall of said member being about one-eighth ($\frac{1}{8}$) inch at about the medial point of said member and increasing gradually to about one-fourth ($\frac{1}{4}$) inch, the length of said member between the two points where the thickness reaches about one-fourth ($\frac{1}{4}$) inch being about seventeen (17) inches, said wall having a rounded edge. 110 115

9. In a collar-fold ironing device, an ironing element comprising a partially cylindrical member open at one side of the cylinder, the thickness of the wall of said member being about one-eighth ($\frac{1}{8}$) inch at about the medial point of said member and increasing gradually toward both ends to about one-fourth ($\frac{1}{4}$) inch, the length of said member between the two points where said thickness reaches about one-fourth ($\frac{1}{4}$) inch being about seventeen (17) inches, and then extending from each of said two points for about two and one-half ($2\frac{1}{2}$) inches with a thick- 120 125 130

ness of about one-fourth ($\frac{1}{4}$) inch, said wall having a rounded edge.

10. A collar-fold ironing device, comprising a partially cylindrical member open at one side of the cylinder, the thickness of the wall of said member increasing from a point midway the ends thereof toward said ends, and a second member having a curved indented portion so shaped and dimensioned as to fit with a slight degree of play over the thickest portion of said edge.

11. A collar-fold ironing device, comprising a partially cylindrical member open at one side of the cylinder, the thickness of the wall of said member increasing from a point midway the ends thereof toward said ends, and a second member having a curved indented portion so shaped and dimensioned as to fit with a slight degree of play over the thickest portion of said edge, said second mentioned member being mounted for movement along said edge and transversely of said edge.

12. A collar-fold ironing device, comprising a partially cylindrical member open at one side of the cylinder, the thickness of the wall of said member being about one-eighth ($\frac{1}{8}$) inch at about the medial point of said member and increasing gradually toward both ends to about one-fourth ($\frac{1}{4}$) inch, the length of said member between the two points where said thickness reaches about one-fourth ($\frac{1}{4}$) inch being about seventeen (17) inches, and then extending from each of said two points for about two and one-half ($2\frac{1}{2}$) inches with a thickness of about one-fourth ($\frac{1}{4}$) inch, said wall having a rounded edge, and a second member having a curved indented portion so shaped and dimensioned as to fit with a slight degree of play over the thickest portion of said edge.

13. A collar-fold ironing device, comprising a partially cylindrical member open at one side of the cylinder, the thickness of the wall of said member being about one-eighth ($\frac{1}{8}$) inch at about the medial point of said member and increasing gradually toward both ends to about one-fourth ($\frac{1}{4}$) inch, the length of said member between the two points where said thickness reaches about one-fourth ($\frac{1}{4}$) inch being about seventeen (17) inches, and then extending from each of said two points for about two and one-half ($2\frac{1}{2}$) inches with a thickness of about one-fourth ($\frac{1}{4}$) inch, said wall having a rounded edge, and a second member having a curved indented portion so shaped and dimensioned as to fit with a slight degree of play over the thickest portion of said edge, said second mentioned member being mounted for movement along said edge and transversely of said edge.
